EXPANDABLE CARRYING BAG

Anthony N. D'Elia, Riverdale, and Edward M. Stolarz,
Yorktown Heights, N.Y., assignors to Reliable Luggage,
Incorporated

Filed Jan. 25, 1968, Ser. No. 10,314

Term of patent 14 years

Int. Cl. D3—02
U.S. Cl. D87—5

FIG. 1

FIG. 2

FIG. 3

FIG. 5

FIG. 1 is a perspective view of an expandable carrying bag embodying our new design, shown in the closed position, the slide fastener being closed and the flaps being tucked in;

FIG. 2 is a perspective view of the expandable carrying bag shown in an open position, the slide fastener being open and the side flaps being upright;

FIG. 3 is a side elevational view thereof shown in an open position, the opposite side being identical;

FIG. 4 is a top plan view thereof; and

FIG. 5 is a bottom plan view thereof.

We claim.

The ornamental design for an expandable carrying bag, as shown and described.
